UNITED STATES PATENT OFFICE.

ALBERT F. TREMBLAY, OF THREE RIVERS, TEXAS.

GLASS-CHARGING DEVICE.

Application filed July 2, 1927. Serial No. 203,127.

The present invention relates to improvements in glass charging devices, and has for an object to provide an improved device for supplying measured charges of molten glass to a circular or other bottle forming machine in which the molds for the bottles are arranged circularly and revolved about beneath the glass charging apparatus from which they receive gobs of the molten glass.

Another object of the invention is to provide a glass charging machine in which shears are provided, operated concurrently with the discharge plunger for severing the glass gob, whereby to promote uniformity in the gobs supplied to the molds and the consequent uniformity in the character of the bottles produced.

Another object of the invention is to provide a mechanical apparatus for carrying out the above purposes, which will be of great simplicity in construction, although having a high degree of flexibility whereby necessary adjustments may be made with ease through a minimum amount of parts.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation, with parts broken away, of a glass charging machine constructed according to the present invention.

Figure 2 is a plan view, with parts in section of the shears.

Figure 3 is a section taken on the line 3—3 in Figure 2.

Figure 4 is an enlarged elevation of the plunger and supporting mechanism with parts indicated in section.

Figure 5 is a top plan view of the plunger head.

Figure 6 shows a slight modification of plunger with parts in section and parts broken away, and

Figure 7 is a vertical central section taken through the plunger reciprocating means of Figure 1.

Referring more particularly to the drawings 7 and 8 represent a portion of the framework for holding the reservoir 9 for the molten glass, which is adapted to descend

through the central opening 11 of the reservoir, being aided thereto by the action of the vertically reciprocating plunger 12.

This plunger is carried by a shaft 13 which slides axially through a rotary sleeve 14 and the shaft is secured by the key 15 through its non-rotating bearing 18' in the beam 18, which key permits of axial movement of the shaft but not rotary movement. The sleeve 14 is rotated by the action of a chain 16 trained about a sprocket 17 fixed to the sleeve above the beam 18 in which the sleeve 14 is free to rotate, but fixed against an axial motion.

The upper surface of the sleeve 14 is formed into a cam track 19 traversed by a roller 20 supported upon the upper portion of the shaft 13 as by a yoke 21, which is provided with the lower and upper collars 22 and 23 adjustable longitudinally on the shaft 13 but normally fixed against any relative axial motion. The collar arms of the yoke are provided with the bearings 24 and 25 in which is journaled to rotate a threaded shaft 26 passing through and having threaded engagement with a bolt head 27, the shank 28 of which extends transversely through the shaft 13. This shank 28 may be placed in one or more transverse openings 29 in the shaft.

The lower end of the screw adjusting shaft 26 is coupled as by the universal connection 30 with an adjusting rod 31 having at its lower end the handle 32 located in a convenient position close to the motor unit 90 and to the hand of the operator.

Now the chain 16 is trained over a sprocket 33 on the drive shaft 34 extending down into the gear box 35 and driven by the worm gearing 36 from the counter shaft 37 having the pinion 38 meshing with the motor pinion 39 on the armature shaft 40 of the electric or other motor 41.

As shown in Figure 4 the shaft 13 is formed with a reduced nipple 42 providing a shoulder 43 thereabout against which the driving disc or head 44 abuts, the nipple 42 projecting down through a central opening in the driving disc and therebeyond to fit into a socket 45 made in the head 46 of the plunger 12. The driving head 44 is provided with the screw 47 at one side and with the hinged bolt 48 at its other side fitted for swinging movement in the socket 49. The plunger head 46, as shown in Fig-

ure 5, is provided with the bifurcated diametrically disposed lateral arms 50 and 51. In the slot 52 of the arm 50 the screw 47 is adapted to fit, while in the slot 53 of the opposite arm 51 the hinged bolt 48 is adapted to swing down, as indicated in Figure 4. The screw 47 and the nut 54 on the hinge bolt 48 may be tightened to bind the plunger head 46 and plunger 12 in the dotted line position, indicated in Figure 4, which is the normal operative position. The nipple 42 acts to center the plunger. By unscrewing the screw bolt 47 and the nut 54, the hinged bolt 48 may be swung out of the socket 53 permitting the plunger head 46 to drop down and be removed from the screw 47 by a lateral movement.

In Figure 6, the plunger 12^a made of clay or other appropriate material is shown as having a head 55 seated upon a shoulder 56 in the socketed head piece 57 provided with the slotted arms 58 and 59 adapted to engage the driver disc 44 in the manner shown in Figure 4. A nut 60 is threaded, as indicated at 61, into the upper portion of the socket of the head piece 57. This nut 60 is provided with the sockets 62 for a spanner wrench and in the center is provided the depression 63 for receiving the tip of the nipple 42 in Figure 4. The nut 60 is adapted to engage the upper rounded surface of the washer 64. In this case the head piece may be removed from the plunger.

Referring now more particularly to Figure 2, the shears are shown which operate just beneath the glass reservoir 9 to sever the gobs of glass. These shears include blades 64 and 65 of well known notched form. The blades are carried by the arms 66 and 67 fulcrumed at 68 and 69 and having the tail pieces 70 and 71 carrying the rollers 72 and 73. These rollers are disposed in the path of the rotary cam 74 having the oppositely extending high points or lobes 75 and 76. The cam 74 is affixed to a shaft 77. To this shaft is also affixed a sprocket 78 driven by the chain 79 from the drive shaft 34.

Upon this drive shaft is fixed a hub 80, as shown in Figures 2 and 3, as by the key 81, so that the hub and a worm wheel 42 formed therewith are compelled to rotate with the drive shaft 34. The sprocket 83 which engages the chain 79 is loosely mounted about the hub 80 and is driven through the worm 84, which is carried upon the side of the sprocket 83 as by the arms 85 and is disposed in mesh with the worm wheel 82. The worm is adjusted as by the detachable adjusting wrench 86.

The shears being closed by the cam arrangement are intended to be opened by action of the pneumatic engine shown which consists of the cylinder 87 having the two pistons 88 and 89 therein coupled by the

connecting rods and links 90 and 91 to the arms 66 and 67. The air is let in centrally through the port 92 through a pipe 93, which communicates with a source of compressed air and with any appropriate type of valve 70 action for admitting this air periodically to the cylinder 87.

In operation the plunger 12 will be constantly reciprocated in the molten metal which is at a very high temperature. Consequently the plunger wears out rapidly or is fractured and requires replacing. Due to the intense heat encountered by the workmen while changing the plunger, the invention is concerned in Figures 4, 5 and 6 with 75 the simplified arrangement of holding and changing of the plunger. As a consequence this work may be carried out more rapidly and at the same time improving the conditions for the workmen. Furthermore, a 80 compact and positive means is provided for holding the plunger to the shaft during operation. The washer 64 in Figure 6 is rounded in order that the pressure of the nut 60 may be always in the center regardless of 85 the uneven top surface of the plunger. This arrangement makes the device self-centering.

The plunger 12 is driven rapidly from the cam track 19 engaging beneath the roller 95 20 and consequently raising the shaft and permitting it to fall. It will be noted that the cam 19 is cylindrical and is concentric with the shaft 13 carrying the roller 20. This makes a more compact and less complicated arrangement than where the cam is remote from the shaft and operates through levers.

Most glass severing devices are air operated and not positive so that a slight variation in the pressure causes a fluctuation in the time of severing one charge of glass to the other. This fluctuation results in a difference in weight between the charges. However, the glass severing apparatus, as 105 shown in Figure 2, is operated by the electric motor through a positive mechanical drive, which drive incidentally also drives the plunger operating mechanism, thereby insuring a perfect timing between the charge 110 producer 12 and the severing device. The cam device 74 closes the blades and the air device 87 subsequently opens the blades. A slight pressure is maintained in the cylinder 87 at all times to keep the arms 66 and 67 115 from closing too hard and to eliminate friction.

The time of severing the charge, in connection with the plunger 12, which regulates the shape of the charge, can be adjusted by 120 turning the hand wheel 86. This causes a walking of the worm 84 about the worm wheel 82 carrying the sprocket 83 therewith, so that the position of the cam device 74 is altered with respect to the drive shaft 34, 125 130

which is not angularly displaced during this adjusting movement. If the severing blades 64 and 65 are timed to cut just when the plunger 12 has finished its downward stroke, 5 having pushed the charge before it, the severed charge will be blunt or large in diameter at the severing point; while, if the blades sever the glass while the plunger 12 is rising, the charge will be pointed or small 10 in diameter at the severing points.

These adjustments of severing the glass at a certain desired point of travel of the plunger 12 to secure the desired shape of charge are accomplished by turning of the 15 worm 84 by the adjusting device 86.

It is obvious that various changes and modifications may be made in the details of construction and design of the above specifically described embodiment of this invention without departing from the spirit thereof, such changes and modifications being restricted only by the scope of the following 20 claims.

What is claimed is:—

25 1. A charge forming device comprising a plunger, a head thereon having slotted arms, a shaft, a driving head on the shaft, a bolt at one side of the driving head to engage one slotted arm of the plunger head, 30 and a hinged bolt at the other side of the driving head to engage the other slotted arm.

35 2. A charge forming device comprising a plunger, a hollow head-piece loosely receiving said plunger, a washer, with rounded face on the plunger, a nut in the head-piece engaging said washer, and a driving part detachably receiving said head-piece.

40 3. A charge forming device comprising a reservoir for molten glass, charge forming means, and charge severing means including shears, cam means to close said shears, and pneumatic means to open the shears.

4. A charge forming device comprising a plunger, a rotary cam concentric with the plunger, a yoke concentric with the plunger 45 and having a roller for riding on said cam, said yoke being slidably mounted with respect to the plunger and cam, and means for causing sliding movement of the yoke on the plunger and for holding the yoke in adjusted 50 position.

5. A charge forming device comprising a plunger, a rotary cam concentric with the plunger, a yoke concentric with the plunger 55 and having a roller for riding on said cam, said yoke being slidably mounted with respect to the plunger and cam, a fixed abutment carried by the plunger, and movable means carried by the yoke and engaging said abutment for adjusting the yoke along the 60 plunger.

6. A charge forming device comprising a plunger, a rotary cam concentric with the plunger, a yoke concentric with the plunger 65 and having a roller for riding on said cam, said yoke being slidably mounted with respect to the plunger and cam, a nut fixed to the plunger, and a screw carried by the yoke and extending through the nut for adjusting the yoke axially on the plunger. 70

7. A charge forming device comprising a plunger, a rotary cam concentric with the plunger, a yoke concentric with the plunger 75 and having a roller for riding on said cam, said yoke being slidably mounted with respect to the plunger and cam, a nut having means whereby it may be secured at any one of a number of points on said plunger, a screw arranged through said nut and being mounted for rotary movement in said yoke 80 but restrained from axial sliding movement, and means connected to said screw for rotating the same to adjust the yoke.
